ATTORNEY

UNITED STATES PATENT OFFICE

IRVING R. DANUFF, OF BRONX, NEW YORK

THREE CIRCUIT FOOT SWITCH

Application filed July 28, 1931. Serial No. 553,536.

This invention relates to improvements in picture projection apparatus, and has as its principal object the provision of means whereby a plurality of projection machines are so controlled that substantially a continuous display of pictures may be thrown upon the screen without break or intermission occurring in changing from one machine to another.

10 A further feature is in the provision of a type of switch adapted to be operated pedally and arranged at a convenient point for the operator, contiguous to each of a series of projection machines.

15 Another purpose is to produce a switch adapted to control current delivered to two or more of the machines, whereby the circuit may be instantly changed from one to another of the machines in the series to open 20 the douser on any one machine, while simultaneously closing the dousers on all other machines in the series.

A still further object is in the provision of a switch using a minimum number of parts, 25 inexpensive to construct, unusually easy to operate, and which dispenses with the cumbersome and complicated multi-conductor system usually employed.

These several important features are attained by the novel construction and combination of parts hereinafter described and shown in the annexed drawing, forming an essential part of this disclosure, and in which:

30 Fig. 1 is a vertical sectional view of an embodiment of a switch made in accordance with the invention, shown in normal position.

35 Fig. 2 is a front elevational view of the same, parts being broken away to show the interior, and illustrated as in a closed or operative position.

Fig. 3 is a diagrammatic view of the electrical circuit and principal instrumentations involved.

40 The switch, shown in considerable detail in Figs. 1 and 2, includes a casing, generally designated by the numeral 10, having on its top or upper surface 11, a cylindrical extension 12 provided with a screw cap 13, the cap and upper wall of the casing containing a cir-

cular aperture adapted to guide an extending plunger 14 provided with a serrated or knurled knob-like head 15.

Fixed to the plunger bar 14 is a collar 16 pressed upwardly against the inner side of the cap 13 by a coiled compression spring 17 encircling the plunger bar at its lower end abutting the upper wall of the casing.

The lower end of the plunger bar is firmly engaged in the raised central hub portion of a dielectric plate 18 having slots 19 formed in its end edges to slidably engage rods 20-21 the upper portions of which are in electrical engagement with contact plates 22-23, the upper terminals of the rods being set in plate insulator 24 secured against the under surface of the top wall 11 of the casing.

Each of the contact plates 22-23 are provided with binding screws 26 by which are secured U shaped spring contacts 27-28 engageable with riveted studs 29-30 extending through the dielectric plate 18 and holding 70 rigidity against its lower surface a plate conductor 31 by which the contacts 27-28 are held in paired relation to normally close the 75 circuit between contacts 27-28, the plate conductor being clear of the plunger bar 14.

Carried by the reduced lower ends of the rods 20-21, which are provided with clamp nuts, is a second dielectric plate 32 on which 80 are engaged a series of spring contacts 33-34-35, held by binding screws 36-37-38 connected respectively with conductors 40-41-42, a similar conductor 39 being clamped by the nut on the rod 21, all 85 these several conductors entering the casing by the cable 43.

The conductor 42 is similarly clamped by a nut to the rod 20 which, by reason of the conductor plate 22, is in electrical engagement 90 with the spring contact 27; it is also in electric engagement with the spring contact 35 by reason of a plate conductor 44 set in the dielectric plate 32.

Under normal conditions the spring 17 holds the knob 15 extended and the contacts 27 and 28 in circuit; upon pressure being applied to the knob 15 the dielectric plate 18 is forced inwardly, breaking the circuit be- 100

tween the contacts 28 and 27, and ultimately closing the contacts 33—34 and 35.

Referring now more to the diagrammatic view shown in Fig. 3, three like shutters or dowsers of any desired type are designated respectively by the numerals 50—50'—50'', the same being arranged closely adjacent to the aperture in each of the three machines used, but it is to be understood that more than three machines may be used, all being controlled in a similar manner and constituting a battery of any desired extent.

These dowsers may be arranged to be operated by T shaped levers 51—51'—51'', by reason of their connections with armature cores 52—52'—52'', each of which extends through pairs of solenoids 53—54, 53'—54', and 53''—54'' each pair being preferably mounted on a common axis and so arranged that the solenoids 53—53'—53'' operate to open the dowsers while the mating solenoids 54—54'—54'' act to close the dowsers.

The particular type of dowsers, armatures and solenoids shown are merely illustrative and no part of the invention, and obviously any type of electrically controlled or operated dowsers may be employed with equal results.

In the illustration, these solenoids are all connected to one leg of the main line 55 by a conductor 57—57'—57''.

When the switches are in normal position as shown in Fig. 1, the circuits to all the solenoids are open and the dowsers remain inactive in either their open or closed positions.

In Fig. 3, dowsers 50'' is shown immediately after it had been opened while the other two are shown closed.

The switch at projector controlled by dowsers 50'' had been depressed, thus opening the circuit between its contacts 27—28, that is between conductors 39'' and 42'', and instead, closing the circuit between its contacts 33—34—35, that is between conductors 40'', 41'' and 42''. Current has passed from conductors 55 through lead 57'', through solenoid 53'' and through leads 40'', 41'' to conductor 56 thus energizing solenoid 53'' causing dowsers 50'' to open. Simultaneously current has passed from conductor 55 through leads 57—57' through solenoids 54—54', —through leads 39—39', leads 42—42', lead 42'', through switch through lead 41'', through conductor 56, thus energizing all the closing solenoids 54—54' to close any dowsers which may be open. The switch is then immediately released breaking all circuits to the solenoids until another change-over is desired.

From the foregoing it will be seen that a simple device for this purpose has been disclosed in the preferred form of its embodiment, but it is not desired to restrict the details to the exact construction shown, it

being obvious that changes, not involving the exercise of invention, may be made without conflict with the scope of the appended claims.

Having thus described my invention, what I claim as new and desire to secure by Letters Patent, is:

1. In a switch adapted to control a plurality of circuits to pairs of solenoids, a casing having a spring raised plunger therein, a plate conductor insulated from and carried by said plunger, a pair of spaced spring contacts insulated from said casing normally in engagement with said conductor a pair of spaced conductor rods acting as guides for said plunger carried plate, said rods being in circuit with a current of electricity, a dielectric plate in which said rods are fixed, a series of spring contacts carried by said dielectric plate, each being in circuit with an electric current leading to other pairs of solenoids, and means to close a circuit from one of the last named contacts with one of the first named contacts.

2. A reciprocating switch comprising a casing, a cylindrical extension above said casing, a screw cap surmounting said extension, a plunger adapted to partially extend beyond the cap, aligned apertures in the cap and the upper wall of the casing adapted to guide the plunger, a collar fixed on said plunger, a coil spring encircling the plunger within the extension and confined between the collar and the upper wall of the casing to urge the plunger outwardly, a bridge conductor carried by said plunger, a pair of spaced contacts normally bridged by said conductor, a pair of spaced conductors being in circuit with an electric current, one of said conductors being in electric engagement with one of said contacts, a dielectric plate in which said conductors are fixed, a series of spring contacts carried by said dielectric plate, each being in circuit with an electric current leading to electrically operated devices, said bridge conductor also serving at times to close the circuit between the said series of spring contacts.

Signed at New York, in the county and State of New York, this 20th day of July, 1931.

IRVING R. DANUFF.
